GASOLINE FIELD STOVE

Leander J. Stein, United States Army,
Sheboygan, Wis.

Application January 4, 1945, Serial No. 571,343

3 Claims. (Cl. 158—63)

(Granted under the act of March 3, 1883, as
amended April 30, 1928; 370 O. G. 757)

1

The invention described herein, if patented, may be manufactured and used by or for the Government for governmental purposes, without the payment to me of any royalty thereon.

This invention relates to stoves and, more particularly, to vapor burning stoves employing a gravity, fuel-feeding system wherein provision is made for automatically utilizing excess vapor generated therein, and returning the same to the fuel supply.

In vapor burning stoves of the gravity fuel feed type, as at present employed, it is necessary to provide some means for disposing of the excess vapor formed in the fuel pipe in order to prevent its deleterious action upon the operation of the stove. If no means of disposal of this vapor is provided, the flame of the burners will be found to pulsate, or ebb and flow, due to the return of the excess vapor to the fuel supply through the fuel pipe. This undesirable effect of excess vapor is especially evident in stoves provided with vapor generators for preheating the fuel before it reaches the burners, in which case the rapidly formed vapor builds up a back-pressure in the fuel pipe, and causes a pulsation of the flame so great as to seriously affect the efficiency of the stove.

Heretofore, attempts have been made to overcome this disadvantage in stoves of this type by extending the fuel pipe beyond the burners to permit excess vapor to pass off without building up undesirable back-pressure therein, or by applying pressure to the fuel pipe sufficient to overcome any back-pressure built up by the formation of excess vapor therein. These expedients have not, however, proved to be entirely satisfactory in a stove of the type here contemplated, because of the unnecessary waste of fuel when using an extension of the fuel pipe and because of the necessity of providing a pump or other means for applying pressure to the fuel when such means is used for overcoming the pressure of the excess vapor.

It is an object of the invention to provide a vapor burning stove having a vapor generating system wherein the above disadvantages are eliminated by the provision of means for the advantageous disposal of excess vapor formed.

A further object of the invention is the provision of a vapor burning stove capable of automatic operation without the necessity for the use of any pump or other agency outside of the stove itself for building up pressure in the fuel supply thereof.

Further objects of the invention are the provision of a stove of the kind named, of simple design and rugged structure, capable of being quickly and easily assembled for operation, or dismantled for transportation, and when so dismantled, occupying a minimum of storage space. A still further object is the provision of a gasoline stove which is easily cleaned and maintained in efficient operation.

10 The above and other objects of the invention are obtained by the provision of a gasoline stove of the gravity fuel feed type, comprising essentially a fuel tank, a vapor generator or expansion chamber and a burner, having a return pipe extending from the generator to the top of the fuel tank for conducting excess vapor to the space above the fuel therein.

The invention will be more fully understood by referring to the embodiment thereof described in 20 the following specification and illustrated in the accompanying drawings wherein:

Figure 1 is a perspective view of the stove with the fuel tank attached thereto, and Figure 2 is an enlarged, sectional view taken along the line 25 2—2 of Figure 1, looking in the direction indicated by the arrows, and showing the structure of one of the burners and the relation of the flame shield to the jet hole thereof. Figure 3 is an enlarged side elevational view of one of the supports 30 of the stove, showing the semi-circular notch therein for the accommodation of the burner section.

Referring to the drawings, the gasoline stove consists of a unit formed of a tube of a suitable 35 material, preferably iron pipe, bent upon itself into a U-shape, as shown in Figure 1, to form an elongated burner section 1 and an elongated vapor generator section 2 extending parallel to, spaced from, and situated above the burner section 1.

40 Any number of burners may be provided, each consisting of a small jet hole 3 in the burner section 1, above which is positioned a flame guard 4 formed of a short section of pipe, of larger diameter than that of the burner section, supported by iron plates 5 welded thereto and to the burner section 1. The burners are arranged at suitable, uniformly spaced intervals along the length of the burner section 1.

45 The unit is horizontally supported upon the standards 6 of T-shape, as shown in Figure 2, having the feet 7 and the uprights 8 formed of angle iron. The uprights 8 are provided with semi-circular slots 9 spaced above the feet 7 into 50 which the burner section 1 is adapted to be re-

ceived, while the generator section 2 rests upon the tops of the uprights 8 along the edges thereof. In this manner, the upper ends of the upright standards 8 provide underneath supports for the generator tube, and the slotted vertical edges prevent the generator tube and burner tube from sliding off laterally; and generator and burner tubes 1, 2 can be disengaged from the upright standards 8 by lifting.

A plug 10 is provided in the end of the burner section 1, affording ready access to the inside thereof for the purpose of cleaning the same.

A section of pipe 11 of smaller diameter than that of the generator 2, and preferably of copper, is coupled to the end thereof and is provided with a screw-threaded, pipe fitting 12. A second screw-threaded pipe fitting 14 is provided on the end of the generator 2. A gasoline well 13 is provided beneath the generator 2 near the fuel receiving end thereof, for the purpose of preheating the generator upon starting operation of the stove. The gasoline well is in the form of a small, shallow, tray-like structure secured to the generator by short supports.

A fuel supply tank 15 is provided, having a filling opening in its top, closed by suitable cap 16. A pipe fitting 17 is provided on the tank at a point near the top thereof, and a needle valve 18 for controlling the flow of the fuel is secured to the tank near its bottom.

A fuel feed pipe 19 extends from the needle valve 18 to the pipe fitting 12 on the pipe 11, whereby fuel is permitted to flow in an amount controlled by the needle valve 18, from the tank to the generator. A vapor return pipe 20 extends from the pipe fitting 14 on the generator section 2 to the pipe fitting 17 near the top of the fuel tank 15.

It will be noted that the burner tube 1 is laterally below the generator or expansion chamber 2, and the vertical axes of burner jets 3 are not directly below generator or expansion chamber 2, but are slightly to one side thereof, so that the burner jets are in heat exchange relation with the chamber 2, but the flame will not play directly on the latter, thus preventing the metal of the same from being rapidly burned out.

The stove is most conveniently set in the ground in a trench, as seen in Figure 1, of such depth as to permit the generator or expansion chamber 2 to lie below the level of the ground, and a sufficient space allowed between the burners and the object being heated for efficient operation of the flame. The stove may also be placed for use directly on the ground, or other support, and provided with a suitable shield for protecting the flame from the wind. The fuel tank is best located at some point of higher elevation than the generator or expansion chamber so that the fuel will be fed to the stove by gravity, and the stove is advantageously placed so that the end thereof nearest the fuel tank is slightly higher than the end remote therefrom, thus permitting liquid fuel to flow into the expansion chamber and promoting vaporization.

In the operation of the stove, a gasoline well 13 is filled with gasoline which is then ignited in order to preheat the generator section 2. When the generator section has been thus sufficiently heated, the needle valve 18 is opened, permitting gasoline to flow to the generator and thence, after vaporization, to the burner section 1 and out through the jet holes 3 where it is ignited. Subsequent heating of the generator section 2 by the burners causes the development of a copious sup-

ply of gasoline vapor with a consequent increase in pressure inside the burner section and generator. If this pressure becomes greater than the burners can accommodate, there is a tendency for excess vapor to flow back through the fuel pipe into the fuel tank. The provision of the vapor return pipe 20 permits this excess vapor to flow into the top of the fuel tank 15 where it accumulates in the space above the fuel therein.

10 The vapor thus returned to the fuel tanks exerts pressure upon the fuel contained therein, making it unnecessary to employ a hand pump or other mechanism for applying pressure to the fuel. The returned vapor is also condensed to liquid gasoline, so that fuel is saved which otherwise would be lost in the operation of a stove not provided with such vapor return means, and thus the economy resulting from the employment of the invention is apparent.

20 When it becomes necessary to clean the interior of the stove, the plug 10 is removed from the end of the burner section 1 and a round, steel brush inserted therein. The jet holes 3 can be easily cleaned by the use of any convenient object such as a piece of wire of suitable diameter.

25 To dismantle the stove, it is only necessary to disengage the fuel and vapor return pipes 19 and 20 which may, for convenience, be flexible, and remove the standards 6. The entire equipment 30 can then be packed into a very small space for transportation. It will thus be apparent that the invention provides an inexpensive and ruggedly constructed stove capable of withstanding the rough usage to which such equipment is likely to be subjected, and having an automatically-operating vapor control and return system which effects a substantial economy of fuel and increased efficiency in operation.

Having thus clearly described the invention, 35 what is claimed and desired to secure by Letters Patent is:

1. A demountable vapor-burner stove comprising an elongated horizontal burner tube, an elongated horizontal generator tube laterally above and communicating with said burner tube, 40 at least one burner jet in said burner tube in heat exchange relation to said generator tube, the vertical axis of said jet being lateral of said generator tube, a plurality of upright standards, the upper end of each of said standards providing 45 underneath support for seating said generator tube, and the vertical edge of each of said standards having means for holding said tubes against lateral displacement, said tubes being disengageable from said standards by lifting.

2. A demountable vapor-burner stove comprising an elongated horizontal burner tube, an elongated horizontal generator tube laterally above and communicating with said burner tube, at 50 least one burner jet in said burner tube in heat exchange relation to said generator tube, the vertical axis of said jet being lateral of said generator tube, a plurality of upright standards, the upper end of each of said standards providing 55 underneath support for seating said generator tube, and the vertical edge of each of said standards being slotted for engaging said burner tube and holding said tubes against lateral displacement, said tubes being disengageable from said 60 standards by lifting.

3. A demountable field stove comprising in combination a closed fuel tank; an elongated horizontal generator tube communicating with said fuel tank; an elongated horizontal burner tube laterally below and communicating with said 75

generator tube; a plurality of spaced vertical burner jets in said burner tube in heat exchange relation to said generator tube, the vertical axes of said jets being lateral of said generator tube; a vapor return pipe leading from said generator tube into said fuel tank at a point above the liquid level in said fuel tank, whereby the contents of said tank are subjected to pressure from vapor returned through said pipe; and a plurality of spaced upright standards, the upper end of each of said standards providing underneath support for seating said generator tube, and the vertical edge of each of said standards having means for holding said tubes against lateral displacement, said tubes being disengageable from said standards by lifting.
